UNITED STATES PATENT OFFICE.

ALFRED A. ZIEGLER, OF BOSTON, MASSACHUSETTS.

RESISTANCE UNIT.

1,115,647.

Specification of Letters Patent.

Patented Nov. 3, 1914.

Application filed March 16, 1914. Serial No. 824,923.

To all whom it may concern:

Be it known that I, ALFRED A. ZIEGLER, a citizen of the United States, residing at Boston, in the county of Suffolk and State 5 of Massachusetts, have invented an Improvement in Resistance Units, of which the following is a specification.

This invention relates to a resistance-unit, and has for its object the construction 10 of a device including a resistance-coil and supporting-means therefor, to which said coil is detachably connected. Such a device is of great value in many forms of signaling, particularly railway-signaling, where 15 resistances of different predetermined values are required, as by providing for the ready removal of the coils from the supporting-means resistances of different predetermined values may be supplied, there- 20 by obviating the necessity of employing variable resistances which require delicate adjustment, and are liable to get out of order.

My invention also has for its object the 25 provision of improved means including attaching-screws for detachably connecting the resistance-coil with its supporting-means, which enables electric connection to be maintained in case the attaching-screw 30 or screws work loose.

Figure 1 is a plan view of a resistance-unit embodying this invention. Fig. 2 is a side-elevation of the same. Fig. 3 is an enlarged vertical longitudinal section of an 35 end-portion of the unit. Fig. 4 is a detail, in plan view, of one of the supporting-plates and an end-portion of the base-block. Fig. 5 is a detail of one of the terminal plates in connection with an end- 40 portion of the resistance-coil. Fig. 6 is an enlarged longitudinal section of the means for detachably connecting a terminal-plate to the supporting-plate. Fig. 7 is an end view of the spool on which the wire of the 45 resistance-coil is wound.

10 represents the base of the unit which is composed of insulating material, such as porcelain. This base consists of an elongated block having holes 12 through it for 50 the screws by which it will be secured to a wall or other support, and having upwardly extended projections 13, at each end, with holes through them to receive screws 14, upon the threaded portions of which are 55 arranged suitable binding-nuts 15, 16, and interposed washers 17, said screws 14 and

nuts and washers arranged thereon constituting the binding-posts. The terminals of the electric-wires 18 are arranged between the washers 17, or they may be otherwise connected with the binding-posts. 60

20, represent flat sheet-metal plates with holes through them for the screws 14, and said plates are arranged on said screws, as here shown, between the outer faces of the 65 projecting-portions 13, of the base-block, and the nuts 15, being held in fixed position by said nuts. Said plates have ears 21 which extend inward toward each other, beyond the inner sides of the projections 13, 70 and said ears have threaded holes through them for screws 22, for the connection therewith of the terminals of the resistance-coil, and said ears also have recesses or notches 23 in their outer ends to receive projections on said terminals. 75

The resistance-coil comprises a spool 25, composed of insulating material, as porcelain, on which one or more layers 26 of fine wire are wound, and said spool has a recess 80 or socket 27 at each end, preferably cylindrical in form, which extends inward a short distance, and at opposite sides of said recesses or sockets grooves 28 are formed, which extend, preferably, the entire length 85 thereof, and the heads or ends of the spool are formed each with a radial groove 29, in extensions of one of the side grooves 28 in the adjacent socket. Terminal-plates are arranged at each end of the spool to which the 90

ends of the coil or coils of wire are soldered or otherwise secured, which plates, as here shown, consists of flat plates 30 of sheet-metal, the inner end-portions of which are made narrower than the outer end-portions, 95 thereby forming a shoulder 31, at the junction of the two end-portions, and said inner end-portions are made of a width corresponding to the diameter of the socket at the grooved portions thereof, so that said inner end-portion may be thrust into the socket 100

with its edges entering the grooves in said socket, thus being held against rotation with respect to the spool, and said inner end-portion is thrust inward until the shoulder 31 enters the radial groove 29 in the end of the spool. When thus thrust into the sockets the outer end-portions project from the ends of the spool. Said terminal plates are additionally secured in place by screws 33 extended through holes in the sides of the 105 spool and through holes in the inner end- 110

portions of the plates, and the heads of said screws 33 may be sunken in holes in the spool and sealed. The outer end-portions of said terminal plates have transversely arranged recesses 35 in their sides to admit of their engagement with the shanks of the screws 22, beneath the heads thereof, which recesses are oppositely arranged with respect to each other. Notwithstanding the screws 22 pass through threaded holes in the supporting-plates 20, there is a tendency for said screws to work loose, and to maintain electric connection in such event, said terminal-plates 30, have projections 36 struck out from them, or otherwise formed on them, which enter the recesses or notches 23 in the outer ends of the ears 21 of the supporting-plates 20. These projections 36 prevent lateral displacement of the terminal-plates with relation to the supporting-plates when the attaching screws become loosened and thus prevent their detachment from the supporting-plates in such event. As the terminal plates are provided with transverse slots in their outer end-portions for quick connection with the attaching-screws, instead of holes through them for said screws, the provision of such projections 36 is of importance, as it enables the employment of terminal-plates with such form of slots, and provides for maintaining electric connection of the plates when the attaching-screws work loose.

In case it is desired to remove a resistance-coil for the substitution of another or for any other purpose, the attaching-screws are loosened sufficiently to admit of disengagement of the terminal-plates therefrom by a movement in a direction lengthwise the screws until the projections 36 have disengaged the supporting-plates and then by a transverse movement, although it will be observed that said movements may be easily and quickly performed by an unskilled person. This is of advantage in railway signal work, as in case a coil burns out another may be easily and quickly substituted for it by an unskilled person. Furthermore, resistance-coils such as herein described of predetermined values have advantages over a variable resistance, some of these advantages being due to the structure and others to the arrangement of the component parts, hence my invention is not limited to the precise structure here shown and described.

I claim:

1. In a resistance-unit, a base-block of insulating material, a pair of binding-posts arranged thereon, a pair of supporting-plates connected with the binding-posts and having ears extended toward each other bearing screws, a spool of insulating material, one or more coils of wire arranged on said spool of a predetermined resistance, terminal plates secured to the ends of said spool to

which the ends of said wire are attached, said terminal-plates extending over the ears of the supporting-plates, and arranged for detachable connection with the screws on said ears, upon a transverse relative movement, said supporting-plates and terminal-plates having co-operating means to hold them against lateral displacement in case the screws work loose, substantially as described. 70

2. In a resistance-unit, a base-block of insulating material, a pair of binding-posts arranged thereon, a pair of supporting-plates arranged in connection with said binding-posts having ears extended toward each other with notches at their extremities, 75 a spool of insulating material, one or more coils of wire arranged on said spool, of a predetermined resistance, terminal-plates secured to the ends of said spool to which the ends of said wire are attached, said terminal-plates extending over the ears of the supporting-plates and detachably secured thereto, and said terminal-plates having downwardly extended projections arranged to enter the notches in said ears, substantially as described. 80

3. In a resistance-unit, a base-block, binding-posts arranged thereon, and a pair of supporting-plates associated with said binding-posts having ears extended toward each other the extremity of each ear having a notch, and a spool composed of insulating-material having one or more coils of wire wound thereon, of a predetermined resistance, and having a socket in each end, terminal-plates at each end of the spool, the inner end-portions of which enter the sockets of the spool and the outer end-portions of which project therefrom, means to secure the inner end-portions in place, the 95 outer end-portions extending over the supporting-plates and having transverse recesses in their sides and screws arranged in connection with the supporting-plates beneath the heads of which said terminal-plates are extended, said terminal-plates also having downwardly extended projections arranged to enter the notches in the supporting-plates, substantially as described. 100

4. In a resistance-unit, a spool composed 115 of insulating-material having one or more coils of wire wound thereon of a predetermined resistance, and having a socket in each end with one or more grooves in its side wall, a terminal-plate at each end of the 120 spool, the inner end-portions of which plates enter the grooves in the sockets in the spool and the outer end-portions of which plates project therefrom, means to additionally secure said inner end-portions in place, the 125 outer end-portions having transverse recesses in their sides to receive screws by which said terminal-plates are detachably connected to their supporting-means, substantially as described. 130

5. In a resistance-unit, a spool composed of insulating-material having one or more coils of wire wound thereon of a predetermined resistance, and having a socket in each end with one or more grooves in its side wall, and a radial groove in its end in continuation of one of the side grooves, a terminal-plate at each end of the spool, the inner end-portions of which plates enter the 10 grooves in the sockets in the spool and the outer end-portions of which plates enter the radial groove and project from the ends of the spool, means to additionally secure the

inner end-portions of said terminal-plates in place, the outer end-portions thereof having recesses to receive screws by which said terminal-plates are detachably connected to their supporting-means, substantially as described.

In testimony whereof, I have signed my 20 name to this specification, in the presence of two subscribing witnesses.

ALFRED A. ZIEGLER.
